APPARATUS FOR DRYING MATERIALS

André Modave, Etterbeek-Brussels, Belgium

Application September 22, 1938, Serial No. 231,261
In Belgium September 25, 1937

2 Claims. (Cl. 34—166)

This invention relates to an apparatus for drying, by means of a current or flow of hot gas, a material which progresses during its drying.

The object of this invention is to adapt the drying of the material, in every point of its travel, to the kind of treatment desired.

In the apparatus of the invention, the saturation point of the drying gas is raised in the course of its travel by introducing in the current, gas containing less vapors than the latter at the spot where the introduction takes place. The gas thus introduced in the current is preferably hot gas which has not yet absorbed vapors evolved from the material to be dried.

The raise of the saturation point can substantially be facilitated by drawing off in addition, gas which contains vapors in the course of the travel of the drying gas.

By drying according to the present invention any condensation of liquid can be prevented inside of the apparatus and upon the material to be dried, without excessively heating said material in any point of its travel and without causing said material to be carried away on account of a too high speed of the drying current. Furthermore, it reduces the duration of the drying because it accelerates the evaporation of the liquid to be driven off.

This invention relates further to apparatus for heating by means of a current or flow of gas, of a material which progresses during its heating.

When a material is heated in an apparatus by means of a current of hot gas, the temperature of the heated current of gas generally decreases progressively from the entrance to the exit of the apparatus.

Now, it is sometimes desirable in practice to vary sharply the temperature of the heating gas in some regions of its travel and particularly to raise the temperature of said gas.

Heretofore, when a heating of this kind was needed, the material to be treated was made to pass successively in different apparatuses, heated independently from one another, each of them at the required conditions of temperature. The material was consequently not shifted continuously during its heating and was exposed to a substantial cooling during its transfer from one apparatus to another.

The present invention aims to remove these disadvantages.

According to the invention the temperature of the heating gas is varied during its travel, by introducing in the current of heating gas, gases of a temperature differing from that of the heating

gas at the point where the introduction is effected.

The drying apparatus according to the invention comprises in the circuit of the drying gas at least one means for removing gas containing vapor and at least one means for introducing gas containing less vapor than that into which the latter gas is introduced.

The invention relates furthermore to a material drying apparatus in which the material to be dried progresses, during its drying under the action of a current of hot gas.

The apparatus according to the invention comprises, several fixed containers located one above another, in a tight casing in which the hot gas circulates, and communicating two by two so that the material introduced in the uppermost container may fall from one to the next, said containers being provided with material shifting means so that said material progresses in each 15 container in the opposite direction to that adopted for one or the other of the adjacent containers.

This apparatus has the advantage that its construction is simple, comparatively cheap and 20 not cumbersome.

The apparatus can furthermore, with advantage, be provided with gas inlet devices and gas outlet devices in various places of the casing and of said containers, which permit either the temperature of the drying current to be varied or the temperature to be varied and the saturation 25 point of said current to be raised.

This invention relates finally to a drying apparatus in which the material progresses by the 30 action of screws during its drying.

In the drying apparatus of this kind, the material is generally moved by a screw secured to a rotating drum containing the material.

In the apparatus according to the invention, 35 the material progresses in a fixed container which contains it, under the action of two adjacent screws having their axes parallel and rotating one towards the other upwards.

This apparatus causes a division and a breaking up of the lumps of the moving material by crushing said material which tends to clog up in lumps on account of its drying. In order to increase this breaking up action, the screws have preferably different pitches. In case these screws are located inside of superimposed containers in which the material circulates successively, while reversing each time its direction, the screws are driven in a very simple way and without great resistance, as follows: the screws contained in two 40 fixed containers located immediately one above

the other and rotating in opposite directions are secured to toothed wheels mounted in the same plane and driven by a driving chain passing around them, the toothed wheels of the screws which are placed one above the other and which rotate in the same direction being located in different planes.

Other features and details of the invention will appear in the following description of the accompanying drawings which represent diagrammatically and only by way of example an embodiment of this invention.

Figure 1 is a diagrammatical vertical and longitudinal section of an apparatus according to the invention.

Figure 2 is a vertical and longitudinal section of a modification, taken along line II-II of Figure 3.

Figure 3 shows in plan said apparatus without the screw driving mechanism.

Figures 4 and 5 are vertical sections taken along lines IV-IV and V-V respectively of Figure 3, up to the heating furnace level exclusively.

Figure 6 shows at a greater scale the part of section IV-IV at the level of container 4.

Figure 7 is a diagrammatic plan of two adjacent screws causing the progress of the material in one container.

Figure 8 is a lateral view of a modification of one of the screws which convey material.

Figure 9 is a front view of driving mechanism for the conveying screws of the apparatus according to Figures 2 to 5.

Figure 10 is a perspective view of a plant of several juxtaposed drying apparatus.

In these various figures, similar reference characters refer to identical elements.

Referring to Figure 1, a drying apparatus is shown comprising four fixed superimposed containers indicated by 2, 3, 4 and 5. These containers communicate with one another through ducts 6, 7 and 8. The material to be dried is introduced at one end of the uppermost container 2 by means of a hopper 9 and progresses towards the opposite end, where duct 6 opens, due to the rotation of screws, only one of which is shown in 10. The material is conveyed in the opposite direction in the container 3 immediately below compartment 2, by means of the rotation of screws such as 11 the thread of which is directed in the opposite way of the thread of screws such as 10. In the containers 4 and 5 are mounted screws such as 12 and 13 similar respectively to screws 10 and 11.

The various containers 2 to 4 are mounted in a tight casing divided in as many compartments as there are containers. The containers of the apparatus shown are indicated by 14, 15, 16 and 17. A partition 18 separates the compartments 14 and 15, a partition 19 separates the compartments 15 and 16 and a partition 20 separates the compartments 16 and 17 while a partition 21 acts as the bottom of the lower compartment 17.

The compartments 14 and 15 communicate with one another through lateral ducts such as 22 which connect two of the adjacent ends of these compartments while compartments 15 and 16 communicate with one another by means of ducts such as 23 located at the other end. Ducts such as 24 connect the compartments 16 and 17 under the same conditions as the compartments 14 and 15 communicate with one another through ducts 22.

The end of the lowermost compartment 17 opposed to that where the ducts 24 open is con-

nected by means of a flue 25 to a furnace 26, while the end of the uppermost compartment 14 opposed to the end where the ducts 22 open is connected by a short pipe 27 with the interior of the uppermost container 2.

The lowermost container 5 is provided with a means for the outlet of the gases contained therein into a main 28 with which a fan 29 is connected which draws the gases from said main.

10 This drawing off means comprises for example a duct 30 in which a means controlling the flow of gas which should pass through it, is mounted. This controlling means is shown as a throttle 31. The other containers 4, 3 and 2 and the compartments 17, 16, 15 and 14 are also provided with a drawing off means constituted by a duct indicated respectively by 32, 33, 34, 35, 36, 37 and 38. Each of these ducts contains a flow controlling means shown as a throttle and referred 20 to respectively by 39, 40, 41, 42, 43, 44 and 45.

The furnace 26 communicates also with a main 46 by means of a flue 47. The main 46 can be connected with each of the containers 2, 3, 4 and 5 and with each of the compartments 14, 15, 16 and 17 by means of gas introducing means constituted by a duct indicated respectively by 48, 49, 50, 51, 52, 53, 54 and 55. In each of these ducts, there is a controlling means which controls the gas allowed to pass and which is shown as 30 a throttle and indicated respectively by 56, 57, 58, 59, 60, 61, 62 and 63.

In each of the ducts 48 to 55, between the respective throttle and the main 46, opens a nozzle shown respectively as 64, 65, 66, 67, 68, 69, 70 and 71. Each of these nozzles opens, on the other hand, in the atmosphere, which provides a cold gas supply as compared with the furnace 26.

In each of the nozzles 64 to 71, an organ has been provided, which controls the flow which 40 may pass and which is shown in the form of a throttle indicated respectively by 72, 73, 74, 75, 76, 77, 78 and 79.

The flues 25 and 47 are further provided with air inlets 80 and 81 and with flow regulating 45 means 82 and 83. In addition, flues 25 and 47 are provided with hot gas flow regulating means indicated by 114.

The material introduced in the apparatus through the hopper 9 passes in succession in 50 the container 2, the duct 6, the container 3, the duct 7, the container 4, the duct 8 and the container 5 before being discharged by means of a gutter 84. In practice, charging through hopper 9 and discharging through gutter 84 are carried out so as to prevent any entrance of air in the apparatus.

Drying is carried out by the heating of the material by the gases which circulate first at the outside of the containers 2 to 5, following a circuit hereinafter called "primary circuit" and afterwards in the inside of said containers following a circuit hereinafter called "secondary circuit."

The hot gases of furnace 26 are introduced in 65 the apparatus through flue 25, after having, if desired, their temperature lowered to the desired degree by introduction of air at 80. From the lowermost compartment 17 in which they are introduced, they pass through the ducts 24, the compartment 16, the ducts 23, the compartment 15, the ducts 22 and the compartment 14. During their entire displacement, they travel at counter-current to the material which moves in the containers they come in contact with from 70 75 the outside.

From the upper compartment 14, the gases enter the uppermost container 2 through the duct 27 and thence they travel parallel with the material to be dried and in the same direction until they are drawn out through duct 30 in the main 28.

The relative speed of gases and material is thus equal to the difference of their absolute speeds, which tends to prevent the dried matter from being carried away. This advantage is most noticeable in the ducts 6, 7 and 8 where the speed of the falling material is substantially greater than the speed of progression in the containers under the action of the screws.

During their travel in contact with the material, the drying gases become loaded with vapor. In proportion as they absorb vapor they approach their saturation point. In order to avoid condensations, they can be maintained below that point, by the introduction of hot gas, proceeding from the furnace 26, and which consequently is not yet loaded with vapor. An introduction of that kind has been shown diagrammatically in the duct 50 by the opening of the throttle 58. The temperature of the additional gas thus introduced in the secondary circuit at the end of the container 4 depends not only upon the temperature of the gas coming out of the furnace 26 but also upon the extent of opening of the throttle 83, which allows the air to enter the flue 47. The temperature of the gas introduced into container 4 can, if desired, be exactly controlled by opening more or less the throttle 77 inside of the nozzle 69 which opens into duct 58.

It should be noted that the raise of the saturation point of the drying gas which comes into contact with the material must not necessarily be accompanied by a raise of temperature. In case the material is dried at a relatively low temperature, the introduction of atmospheric air, even when colder than the gas circulating in the apparatus, could have as a result a raise of the saturation point in spite of the lowering of the temperature of the mixture. The nozzle 74 which introduces the atmospheric air should in such case open in duct 50 down stream of the throttle 58.

The raise of the saturation point of the drying gas is facilitated by the removal of vapor loaded gas, which takes place through the duct 40, due to the opening of the throttle 33. The withdrawal thus made has as a result the lowering of the speed of the gas down stream and prevents thus the dry material from being carried away by the introduction of new quantities of hot gas.

Due to the different ducts connected between the containers 2 to 5 and main 46 on one hand and main 28 on the other hand, the drying gas can easily be maintained in a state such that no condensation takes place in the apparatus. Thereby not only the apparatus is better preserved, but a quicker and more extensive drying is attained. According to this invention, the slimes of coal washing plants containing up to 50% water can easily be thoroughly dried.

The apparatus shown in Figure 1 allows also the reheating of the drying gas while it strikes along the outside of the containers containing the material to be dried. Such a reheating can for example be carried out, by opening the throttle 60, which allows the entry in compartment 14 of hot gas, the temperature of which can be controlled by the opening of the throttle 76. 75

The reheating of the gas in the primary circuit is necessary not only to maintain the gas at the desired temperature up to the end of the primary circuit without superheating at the beginning of said circuit but also to cause a sharp rise in some places of the circuit.

When treating products there may be indeed an interest in heating first moderately and afterwards more intensively. This may be the case 10 when the heating gives rise to a chemical reaction or to a series of chemical reactions.

Assume two bodies in presence which should react during their passage through the apparatus, the reaction starting only when primed 15 by raising the bodies to some given temperature. If the reaction evolves heat, it may be necessary to moderate the heating down stream of the spot where the reaction has started. If then another reaction should take place (for example after addition of other bodies) and if that new reaction takes place only at a temperature higher than that reached during the first reaction, it becomes necessary to heat more intensively down stream of the place where the first reaction came to its end. The apparatus shown in Figure 1 allows perfectly a heating of that kind to be carried out even when the main purpose is not to dry the material.

Some gas inlet ducts and gas outlet ducts may 30 theoretically be considered as superseding other ones because they open in places of the heating circuit between which there is practically no change of state of the gas. The same applies to all the ducts opening in the containers, such as 35 2 to 5 or in the compartments such as 14 to 17, near the duct connecting two adjacent containers or two adjacent compartments with one another.

It may however be considered that in practice 40 the use of two ducts near a connection between two containers or two compartments may allow control of the inlet or the outlet of gas more accurately than it would be possible with one single duct. If such an accuracy is not 45 needed the throttle of only one of both ducts is of course opened.

In Figure 1, the various compartments are shown as if they were identical and consequently 50 interchangeable. In practice, the lowermost compartment could of course be made without any duct such as 32 serving to connect it with main 28. If said compartment is provided with a duct 32, its throttle 39 is of course kept closed to prevent the direct passage into the main 55 28 of the heating gases coming from the furnace 26.

As a principle, the apparatus shown in Figures 2 to 5 is identical to the apparatus diagrammatically shown in Figure 1.

There are two mains 46 for the additional heating gases, one on each side of the same end of the compartments and containers. There are also two mains 28 for conveying the gases to the fan 29. These two mains are located 65 at the other end of the compartments and containers. The ducts 22, 23 and 24 which connect two adjacent compartments are also distributed on either sides of the compartments so that the gases split into two symmetrical currents referring to the middle vertical and longitudinal plane of the apparatus.

Each of the containers 2 to 5 comprises a closed trough, such as trough 4a (Figure 6) suspended by means of angle irons 85 and bolts 86 on a plate which serves as a cover for said con-

tainer and rests on the flanges of angles 87 mounted upon the interior side of the lateral walls 88 of the casing in which the container 4 is placed. The cover plate of the trough 4a serves at the same time as the bottom 19 of 5 the compartment 15.

The progression of the material in each trough is brought about by the rotation of two adjacent screws having parallel axes and turning, one towards the other upwards.

The screws mounted in container 4 are indicated by 12 and 12'. They turn respectively in reverse directions, as shown by the arrows X and X' in order to lift the material between them while conveying it forward. Owing to this movement of the screws, the matter displaced by the screw 12 is crushed against the matter displaced by the screw 12'. This crushing has a great advantage every time the material tends to clog during its drying as is the case in drying clay containing slimes.

In order to increase this crushing and consequently the breaking-up of the lumps, the screw 12 is given a slightly different pitch from that of screw 12'.

Figure 7 shows as an example a screw 12 having a slightly greater pitch than screw 12'.

The screws 10 and 10' in the container 2, the screws 11 and 11' in the container 3 and the screws 13 and 13' in the container 5 are similar to screws 12 and 12' in the container 4 and work under the same conditions.

Experience proves that the breaking-up of the material is more efficient when screws 10 to 13 and 10' to 13' are made discontinuous. Each screw comprises then, as shown in Figure 8, a plurality of blades 89 inclined in respect to the axis of the shaft 90 on which they are secured. In practice these blades need not to have helical surfaces but they can be made of simple plane sheets inclined in respect to the axis of the shaft 90.

The ends of the shafts of both screws mounted in the same container pass through plates such as 91 (Figures 2 and 6) which close openings 92 left in walls 93, located at the ends of the containers 2 to 5 and of the compartments 14 to 17. These openings 92 are great enough to allow the passage of the two screws in front of which they are managed.

The plates 91 carry bearings for the trunnions of the screw shafts. These bearings can, if necessary, easily be cooled by water circulation.

To rotate the various screws 10 to 13 and 10' to 13' in the proper direction, a particularly simple and efficient mechanism has been provided.

The shafts of the screws such as 10 and 11', which turn respectively in opposite direction in two adjacent containers, carry toothed wheels 94 and 95 (Figures 2 and 9) located in the same plane. The other screws 12 and 13' rotating under the same conditions carry also upon their shaft each a toothed wheel indicated respectively by 96 and 97 and located in the same plane as toothed wheels 94 and 95.

The shafts of screws 10', 11, 12' and 13 carry each a toothed wheel indicated respectively by 98, 99, 100 and 101. The latter wheels are all located in the same plane different of that containing the wheels 94 to 97. They are for example further away from the casing than said wheels 94 to 97.

A chain 102 meshes with the wheels 94 to 101 and idling wheels 103, 104, 105 and 106. The 75

wheels 103 and 106 are lower than the wheels 97 and 101 pertaining to the lowermost container, while the wheels 104 and 105 are higher than the wheels 98 and 99 pertaining to the uppermost container. The wheels 104 and 106 are located in the same plane as the wheels 94 to 97, while the wheels 105 and 103 are located in the same plane as the wheels 98 to 101.

The chain 102 passes from one plane to the other either running upwards from the lower idler 103 to the upper idler 104, or running upwards from the lower idler 106 to the upper idler 105.

The lower idler wheels 106 and 103 are keyed to shafts indicated respectively by 107 and 108. These shafts carry in the same plane toothed wheels indicated respectively by 109 and 110 with which mesh a chain 111 driven from a motor 112 by means of a speed reducer.

When several apparatus such as that just described are needed to handle a given amount of material, they can be juxtaposed with advantage as shown in Figure 10.

In such case, the chains such as 102 of the various apparatus are driven from a common motor 112 by means of a chain 111 meshing with the toothed wheels 109 and 110 of each apparatus.

The space between two adjacent apparatus is closed in all directions by sheet iron such as 113 which can be insulated against heat at the same time as the outer sides of the apparatus. The sides of these apparatus which are located in front of each other need not be heat-insulated as the heat radiated by any one side serves to heat the side in front of the latter.

In case each apparatus comprises an uneven number of superimposed containers, two chains are used to drive the toothed wheels keyed upon the shafts of the conveying screws, each of these chains moving exclusively in the plane of the wheels it drives.

The invention is of course not exclusively limited to the embodiment shown and described and many modifications can be made to the form, the arrangement and the construction of some of the elements entering in this embodiment without to exceed the scope of the appended claims.

What I claim is:

1. Drying apparatus comprising fixed superimposed containers containing the material to be dried, adjacent screws in each of said containers having their axes parallel and rotating one towards the other upwards, the pitch of said screws being inclined in such a direction that the material progresses in each container in the direction opposite to that adopted for any one of the adjacent containers, toothed wheels secured to said screws, the toothed wheels corresponding to screws placed immediately one above the other and rotating in a direction opposite to one another being located in a same plane while the toothed wheels corresponding to screws which are placed immediately one above the other and which rotate in the same direction are located in different planes, a driving chain meshing with the toothed wheels, communicating ducts between the containers, so arranged that the material in one container may drop from it to the next, a tight casing in which the containers are disposed, and means for circulating hot gas in said casing.

2. Drying apparatus comprising an even number of fixed superimposed containers containing the material to be dried, adjacent screws in each of said containers having their axes parallel and

rotating one towards the other upwards, the pitch of said screws being inclined in such a direction that the material progresses in each container in the direction opposite to that adopted for any one of the adjacent containers, toothed wheels secured to said screws, the toothed wheels corresponding to screws placed immediately one above the other and rotating in a direction opposite to one another being located in a same plane while the toothed wheels corresponding to screws which are placed immediately one above the other and which rotate in the same direction are located in different planes, two idling toothed wheels one of which

is located higher than the toothed wheels corresponding to the uppermost container and the other is located lower than the toothed wheels corresponding to the lowermost container, one single chain meshing with all the toothed wheels and passing from one plane to the other between the two said idling toothed wheels, communicating ducts between the containers, so arranged that the material in one container may drop from it to the next, a tight casing in which the containers are disposed, and means for circulating hot gas in said casing.

ANDRÉ MODAVE.
